PACKAGING OR CRATING STRUCTURE

Harry C. Way, Wheeling, W. Va.

Application July 13, 1938, Serial No. 219,038

3 Claims. (Cl. 206—60)

This invention relates to packaging or crating structures, capable of general use but particularly intended for the packaging or crating of sheet materials, such as tin plate, and has particular reference to improvements in packaging or crating structures of the general type described and claimed in my prior Patent No. 1,910,783, dated May 23, 1933.

Generally speaking, the object of the present invention is to provide a packaging or crating structure of the general type referred to which is highly efficient in use and which, at the same time, is quite simple and of exceptionally low cost.

With the foregoing general object and various other special objects in view, which will become more fully apparent as the nature of the invention is better understood, the same consists in the novel features of construction, combination and arrangement of parts as will be hereinafter more fully described, illustrated in the accompanying drawing and defined in the appended claims.

In the accompanying drawing, wherein like characters of reference denote corresponding parts in related views:

Figure 1 is a perspective view of a package or crate formed in accordance with one practical embodiment of the invention.

Figure 2 is a detail side elevation of one lower corner portion of the package illustrated in Figure 1.

Figure 3 is a detail end elevation of one lower corner portion of the package illustrated in Figure 1.

Figure 4 is a detail horizontal section through one corner portion of the package illustrated in Figure 1.

Figure 5 is a detail perspective view of one upper corner portion of a package in accordance with an alternative embodiment of the invention; and

Figure 6 is a detail section through the top portion of the corner element illustrated in Figure 5.

Referring to the drawing in detail, first with particular reference to the embodiment of the invention illustrated in Figures 1 to 4, 10 designates a stiff base or platform element which may be formed from wood or any other suitable material and which is of a length and width corresponding substantially to the length and width of the package to be formed.

In forming a package according to the invention, the first step is to stack on one of the base or platform elements 10, to any desired height,

the articles, such as a number of tin plate sheets 11, to comprise the package. A stiff top element 12 of wood or any other suitable material and of the same length and width as the element 10, then is placed upon the top of the stack of articles 11, and either prior or subsequent to the placing of the top element 12, sheets 13 of cardboard or other suitable material for the protection of the edges of the sheets 11 preferably, but not necessarily, are placed against the sides and the ends of the partly formed package. Four duplicate angle-iron members 14 which may be formed from scrap, imperfect or damaged tin plate, or from any other suitable stiff material and which are of pre-formed lengths corresponding substantially to the predetermined height of the package, then are placed vertically against the four corners, respectively, of the partly formed package in embracing relationship to the corners of the platform and top elements 10 and 12 and, of course, in embracing relationship to the corners of the stacked tin plate sheets or other articles disposed between said platform and top elements 10 and 12, the flanges of said angle-iron members 14 overlying the marginal end portions of the protective sheets 13, if such sheets are employed, so that in the finished package the said angle-iron members 14 serve to hold said sheets 13 operatively in the package assembly.

Next, duplicate corner members 15 are placed at the eight corners of the package and by means of a pair of tie wires 16 which are passed across said corner elements 15 and diagonally across the sides and ends of the package, the whole assembly is rigidly bound together in a unitary structure so that any possibility of the tin plate sheets 11 shifting relative to one another is effectively prevented.

The corner elements 15 may be formed from scrap, imperfect or damaged tin plate or from any other suitable stiff, sheet material and each comprises a short-length strip of material of suitable width having its end portions 17, 17 bent in the same direction from the medial horizontal portion 18 thereof along lines diagonal with respect to the strip and with respect to each other so that said end portions lie in planes at right angles to each other and also at right angles to the plane of said medial portion 18. The obliquity of the end portions 17, 17 relative to the medial portion 18 depends, of course, upon the angularity of the lines of bend of said end portions relative to the side edges of the strip from which the corner elements 15 are formed, and in this connection the obliquity of the end portions of

any given set of said corner elements for use with a package of any given height, length and width, is predetermined so that when the said corner elements are applied as illustrated in the drawing, said end portions extend, respectively, toward the diagonally opposite corners of the package. In other words, when the corner elements 15 are applied, the medial portions 18 of the four bottom corner elements underlie the platform element 10 and engage flatly with the under face thereof; the medial portions 18 of the four top corner elements overlie the top element 12 and engage flatly with the upper face thereof; one end portion 17 of each of said corner elements lies flatly against the related side face of the package; the other end portion 17 of each of said corner elements lies flatly against the related end face of the package, and each end portion 17 extends diagonally toward the opposite corner of the related face of the package.

Each end portion 17 of each of the corner elements 15 has a rib 19 pressed outwardly therefrom to provide an inwardly opening channel, and, as shown, said ribs and channels extend transversely of said end portions 17, 17, preferably in divergent relationship, inwardly, with respect to the plane of the medial portion 18. Moreover, each rib 19 is slotted intermediate its ends, as indicated at 20.

Cooperating with each corner element 15 is an L-shaped rod or stiff wire binding element 21, the arms 22 of which embrace the related angle-iron member 14 and are disposed in the aforesaid channels of the corner element end portions 17, 17, respectively, and have outwardly directed U-shaped formations 23 extending through the slots 20.

Starting at one side or end of the package, one of the tie wires 16 extends through the U-shaped formation 23 of one of the arms 22 of one of the binding elements 21, then across the bottom or the top face, as the case may be, of the medial portion 18 of the related corner element 15, then through the U-shaped formation of the other arm 22 of the same binding element 21, then diagonally across the related side, or end, face of the package, as the case may be, to the corner element 15 at the diagonally opposite corner of the package, then through the nearer U-shaped formations 23 of the binding element 21 of the latter corner element, then across the top or the bottom face, as the case may be, of the medial portion 18 of said last mentioned corner element 15, then through the other U-shaped formation 23 of the last mentioned binding element 21, then diagonally across the related side, or end, face of the package, as the case may be, to the corner element 15 at the diagonally opposite corner of the latter side, or end, face of the package where it is cooperatively engaged with said latter corner element and the U-shaped formations 23 of its related binding element 21 as set forth in connection with the two corner elements first mentioned, then diagonally across the related side, or end, face of the package, as the case may be, to the corner element 15 at the diagonally opposite corner of the latter face of the package where it is cooperatively engaged with the last mentioned corner element 15 and its related binding element 21 as set forth in connection with the other corner elements, and, finally, to its starting point where its ends are drawn taut and tied together, as indicated at 24, in any suitable manner. Thus, there results between four corners of the package, all

of which are diagonally opposite each other, a firm binding, which, as is apparent, serves to draw the platform and top elements 10 and 12 upwardly and downwardly, respectively, and acts through the corner elements 15 and their related binding elements 21 to draw the angle-iron elements 14 inwardly, so that the package is, to a major extent, securely trussed.

The other tie wire 16 extends with respect to the four remaining diagonally opposite corners 10 of the package, and to the corner elements 15 and their associated binding elements 21 at the latter corners of the package, in the same manner as the first mentioned tie wire extends with respect to its related corners of the package and their associated corner elements 15 and binding elements 21. Thus, the other four diagonally opposite corners of the package are bound together in the same manner as the four corners first mentioned, and since the two tie wires serve, at all corners of the package, to urge the angle-iron elements 14 inwardly and the platform and top elements 10 and 12 upwardly and downwardly, respectively, the package is securely trussed against any possibility of the sheets or other articles 11 shifting relative to each other and with said sheets or other articles effectively protected by the platform and top elements 10 and 12, respectively, the angle-iron corner elements 14 and the facing sheets 13 if the latter are used.

If the package is of considerable length, or width, one or more tie wires 25 may be extended around the package intermediate its ends, or sides, to assist in holding the medial portion of the package tightly trussed. If a tie wire, or wires 25 is, or are, employed, small abrasion plates 26 may be employed beneath said wire where it extends across the corners of the package to prevent the wire from sinking into the platform and top elements 10 and 12, respectively. In this connection it is apparent that the corner elements 15 serve the same purpose respecting the tie wires 16.

Preferably, the platform element 10 is provided at its under side with two or more battens or cross members 27 to reinforce said platform element and, in particular, to serve as runners to support said platform element above a floor or the like to facilitate tying of the package and either sliding of the same from one position to another or engagement of a hand truck or the like therewith for its transportation from one position to another.

If the members 27 are employed, and if they are located near the ends, or sides, of the platform element 10, they may be slotted adjacent to their ends, as indicated at 28, to accommodate the portions 18 of the corner elements 15.

Instead of employing corner elements 15 of the type illustrated in Figures 1 to 4, corner elements of the type illustrated in Figures 5 and 6 and designated as 15^a, may be used in a structure otherwise the same as illustrated in Figures 1 to 4. The corner elements 15^a may be formed from scrap, imperfect or damaged tin plate or from any other suitable stiff, sheet material and each comprises, as illustrated in Figure 5, two right angularly related portions each of which is of L-shaped cross section and comprises a vertical wall 29 and a horizontal wall 30. The horizontal walls 30 are slit to provide, at the adjacent ends of said walls, tongues 31 which are suitably formed into eyes 32 projecting outwardly from said walls and which have their free ends directed forwardly 75

and suitably curved so that a related tie wire 16 may be engaged in said eyes simply by urging the tie wire rearwardly beneath the free end portions of said tongues as indicated in Fig. 6 of the drawing. The eyes 32, formed as shown and described, serve to retain the tie wire in assembly with the corner element 15^a during initial assembly of the packaging structure. After the tie wire has been tightened and fastened, the eyes 32 may, if desired, be crimped upon the tie wire to secure it against shifting relative to the corner element. Moreover, the eyes 32 may be longitudinally curved as indicated in Fig. 5 so as to avoid cutting by their edges of the tie wire. When the tie wires are tightened the corner elements 15^a are, of course, drawn in the same manner as the corner elements 15 to cause the package to possess the desired attributes of firmness and rigidity. Manifestly, metal bands or other equivalents of the tie wires 16 may be employed in lieu of said wires with either of the two different types of corner elements illustrated or with equivalents of said corner elements.

Without further description it is thought that the features and advantages of the invention will be readily apparent to those skilled in the art, and it will of course be understood that changes in the form, proportion and minor details of construction may be resorted to, without departing from the spirit of the invention and scope of the appended claims.

I claim:

1. A packaged rectangular assemblage of articles comprising a stiff rectangular platform element underlying the articles, a stiff rectangular top element overlying the articles, said platform and top elements being of substantially the same length and width as the article assemblage, vertical elements of stiff sheet material and of 40 L-shaped cross section embracing the vertical

corners of the article assemblage and the corners of the platform and top elements, bottom corner elements having bottom portions underlying the corners of the platform element and side portions embracing lower portions of the side faces of the vertical corner elements, top corner elements having top portions overlying the corners of the top element and side portions embracing upper portions of the side faces of the vertical corner elements, an L-shaped element detachably interconnected with the side portions of each corner element and embracing the related vertical element, and tie elements extending over diagonally opposite of said corner elements and acting through the latter to draw the platform 15 and top elements upwardly and downwardly, respectively, and the vertical corner elements inwardly to securely truss the article assemblage, said tie elements cooperating with said L-shaped elements to draw the latter against said vertical 20 elements.

2. In a packaged assemblage of articles as set forth in claim 1, ribs pressed outwardly from the side portions of the corner elements to provide channels, each rib having a slot, the L-shaped 25 elements having their end portions disposed in said channels, and U-shaped formations in the end portions of said L-shaped elements extending through said slots, the tie elements extending through said U-shaped formations. 30

3. In a packaged assemblage of articles as set forth in claim 1, ribs pressed outwardly from the side portions of the corner elements to provide channels, each rib having a slot, the L-shaped 35 elements having their end portions disposed in said channels, and formations in the end portions of said L-shaped elements extending through said slots and embracing the tie wires, thereby holding the latter operatively positioned.

HARRY C. WAY. 40
